MULTIPOLE CIRCUIT BREAKER

Felix E. Myers, Haddon Heights, N. J., assignor
to I-T-E Circuit Breaker Company, Philadelphia, Pa., a corporation of Pennsylvania

Application October 31, 1951, Serial No. 254,065

5 Claims. (Cl. 200—88)

1

My present invention relates to circuit breakers and more particularly it relates to circuit breakers having more than one pole.

Multi-pole circuit breakers are usually produced and sold by bolting two or three single pole circuit breakers together. Simultaneous operation of all poles was obtained by rigidly tying all the external handles together causing simultaneous closing or tripping of all poles.

My novel invention provides means to considerably improve both operation and appearance of these multi-pole circuit breakers.

Essentially, each pole of my new circuit breaker has its own mechanism which is controlled to open or close by an integral handle operating all poles simultaneously.

Furthermore, each pole is provided with its own fault current responsive means and provided with a common tripper bar so that the automatic opening in one phase produces the instantaneous opening of the other two phases. More specifically, the cradles in each mechanism are coupled together by insulating bars extending through each breaker. The entire cradle unit is latched to a tripping lever at any point, for example, in the case of a three-pole breaker at the center pole and in the case of a two-pole breaker at the left pole. The tripping lever has an insulated bar which extends into the other poles of the breaker so that thermal and instantaneous tripping can be accomplished either independently or in combination by one or more phases.

In assembling my novel circuit breaker, the pole which has the manual operating extension of the integral handle may be assembled first and then work in either direction to build up a two or three pole breaker.

The main object of my present invention is, therefore, the provision of means whereby multi-pole circuit breakers can be easily assembled using practically only parts for single pole circuit breakers.

Another object of my present invention is the provision of means whereby a fault current in any of the circuits protected by my novel multi-pole circuit breaker will open simultaneously all the contacts of my novel multi-pole circuit breaker.

A further object of my present invention is the provision of means whereby the opening and closing of all contacts of the multi-pole circuit breaker can be obtained by the operation of a single handle.

The foregoing and many other objects of my invention will become apparent in the following description and drawings in which:

2

Figure 1 is a sectional view of a two-pole circuit breaker incorporating my novel invention.

Figure 2 is a sectional view taken on line 2—2 of Figure 1, looking in the direction of the arrows.

Figure 3 is a front view of the circuit breaker of Figure 1.

Figure 4 is a sectional view of a three-pole circuit breaker incorporating my novel invention.

Figure 5 is a sectional view taken on line 5—5 of Figure 4, looking in the direction of the arrows.

Figure 6 is a front view of the circuit breaker of Figure 4.

Figure 7 is another sectional view of the two pole circuit breaker taken on line 7—7 of Figure 2, looking in the direction of the arrows.

Referring now to Figures 1 and 2 showing a two-pole circuit breaker in the open position, housing 10 is a shallow box, preferably a plastic insulating molding, having two cover plates 11 and 12, one on each side of housing 10. Cover plates 11 and 12 can be secured to housing 10 in any suitable way, for example, by means of bolts and nuts engaging openings 13 in housing 10 and cover plates 11 and 12, or rivets engaging 25 the same opening 13.

Referring now to the phase of this circuit breaker having the manual operating means as shown in Figure 1, stationary contact assembly 26 consists of a contact button 21, welded or in any other appropriate way secured to the bent 30 end of a conducting member 25. Member 25 with contact button 21 is slideably mounted in an appropriately shaped recess 26 of molding 10, that is, member 25 can be slid in place in housing 10 when cover plate 11 is removed. The other end 30 of conducting member 25 has a central opening 31 threaded inside and engageable by a screw 35. The line terminal of one phase, not shown, can be secured to the circuit breaker by means of screw 35 and extension 30 of contact member 25. The load terminal of the same phase is secured to the circuit breaker at terminal 37. Terminal 37 consists of a screw 38 engaging an opening 39 in an angularly shaped conducting member 40. Conducting member 40 of rectangular cross section is secured to housing 10 by means of a screw 41 engaging through an appropriate opening 42 of housing 10 a threaded opening 43 in conducting member 40. Conducting member 40 is soldered to thermally responsive member 46 and the completed assembly is then drilled and tapped to receive screw 45. Screw 45 is used to adjust the tripping times of each pole of the circuit breaker as hereinafter described.

The other end of thermally responsive member 50 40 is connected by any appropriate means, for

example, soldering to a flexible conductor or pigtail 50. Conducting member 49 is also provided with an integral support 52, consisting of two extensions 53 and 54, one on each side of thermally responsive member 46. Both extensions 53 and 54 extend beyond thermally responsive member 46 and carry at their farthest end a pin 55. A coil spring 60 around pin 55 has one end 61 against a protruding portion 62 of housing 10 and its other end 63 biases a latch carrying member 65.

Latch carrying member 65 consists of a thin metallic leaf 66 approximately U-shaped having at one end extending arms 67 with openings 68 which are engaged by pin 55 so that member 65 can rotate around pin 55. The other end of member 65 is bent and has a U-shaped portion with aligned openings 69 carrying tripper bar 70. Tripper bar 70 is held in place by a bent finger 71 cut from the metallic leaf 66.

Tripper bar 70 is an insulated bar common to the two phases of the circuit breaker; that is, tripper bar 70 extends from the phase of the circuit breaker now under consideration to the second phase of the same circuit breaker, as hereinafter described.

Trip lever 65 is further provided with an armature 72 which is secured to trip lever 65 by any suitable means, for example, a rivet. Armature 72 is the movable part of the fault current responsive magnet 75 which consists of a rectangular piece of metal with a central recess 76 to receive thermally responsive member 46 to which it is also secured by means of a rivet. The same rivet that secures armature 72 to trip lever 65 can be used to secure latch 80 to trip lever 65. Thermally responsive member 46 and magnet 75, as is quite evident, are designed to operate at different values of fault currents. For example, when a fault current is relatively small, the thermally responsive member 46 will operate to open the circuit breaker as hereinafter described. If, on the other hand, the fault current is relatively high, magnet 75 will come into operation before thermally responsive member 46 and open the circuit breaker. This is important in that by this means thermally responsive member 46 is protected against very heavy currents which could permanently distort and damage bimetallic member 46.

Latch 80 carried by trip lever 65 engages a hook-shaped cradle 85 and more precisely latch 80 engages one end 86 of cradle 85. Cradle 85 is pivoted at the other end 87 by means of a pin 88 engaging an opening 89 in cradle 85 and an aligned opening 90 in a boss 91 of molding 10.

It was previously mentioned that screw 45 is used to adjust the tripping time of each pole of the circuit breaker. In fact, since the head of the screw 45 bears against the inner U-shaped pocket 92 of molding 10, any turning of screw 45 will bend the terminal assembly of the thermally responsive member 46. The thermally responsive member 46 then moves the tripper bar 70 and lever 65 to decrease the amount of latch bite between latch 80 and cradle end 86. The tripping times are adjusted by means of a screw driver inserted through a hole 93 in molding 10. After adjustment hole 93 is sealed with porcelain or other insulating compound.

Cradle 85 of the first phase moves together with cradle 185 of the second phase since the two cradles 85 and 185 are connected together by an insulating tie bar 95. Tie bar 95 actually consists of a center insulating sleeve 96 and two

lateral insulating sleeves 97 and 98. Central sleeve 96, cylindrical in shape, has two recesses 99 and 100, one at each end of cylinder 96. Lateral sleeves 97 and 98 instead have an axial or longitudinal opening 101 and 102, respectively.

Cradles 85 and 185 both have an opening 103 near the ends 86 and 186, respectively. Each opening 103 is engaged by the cylindrical extension 104 of a cylindrical pin 105. A metallic hollow cylinder 106 is slid on the extension 104 and riveted there. Thus, cradles 85 and 185 are clamped to pins 105 and will move with pins 105. Sleeves 97 and 98 are placed around pins 105, while sleeve 96 is placed around the hollow cylinders 106, thus completely insulating one phase from the other and making at the same time a mechanism strong enough to resist damage produced by repeated opening or closing operations.

Pin 105 on cradle 85, in the case of the two-pole circuit breaker, has for its purpose in conjunction with resetting pin 156, the aligning of cradle 85. The cradle 85 is, therefore, positioned on one side by pin 105 bearing against cover 11, and on the other side by the shouldered resetting pin 156 bearing against pad 107 on the molding 10. This construction makes the cradle assembly between the poles more rigid and compensates for the unequal loading on the left cradle 85 by the load on the right cradle 185.

Pigtail 50 connected on one side to thermally responsive member 46 is connected on the other side to movable contact arm 110. Movable contact arm 110 is approximately U-shaped or is shaped like a tuning fork, the lowest part 111 of movable contact member 110 carrying an electrical contact 112. The two extensions 115 of contact arm 110 can rotate in groove 118 of handle molding 120. An over center tension spring 125 is connected on one side to movable contact arm 110 through an opening 126 in contact arm 110 and on the other side to cradle 85 through an opening 127 in cradle 85. Cradle 85 is further provided with a pin 130 which engages a slot 131 of a contact kicking member 135. Contact kicking member 135 is pivoted around pin 136 which engages an opening 137 in contact kicking member 135 and an aligned opening, not shown, in molding 10. Contact kicking member 135 is provided with an extension 139 at the end of the contact kicking member 135 opposite that at which it is pivoted.

The function of the contact kicking member 135 is to assist the initial opening operation caused by a fault current; more specifically, it provides a means for kicking the movable contact away from the complementary contact when the spring has been moved over center during automatic opening. In other words, kicker 135 prevents contact 112 from sticking to the stationary contact 21 at fault currents, thus preventing welding of the contacts.

Manual operating handle molding 120 operates simultaneously both contacts of the two phase circuit breaker under consideration. It has, therefore, a single handle 140 with an integral axially extending member 141. This axial member 141 has two pins 142 and 143, one on each side of axial member 141, both integral parts of molding 120. Axial member 141 has two pairs of fulcra 118 and 150 of which, as previously explained, fulcrum 118 is for movable contact member 110, while fulcrum 150 is for movable contact member 155 of the second phase 75 of the two-phase circuit breaker under consid-

eration. Molding 120 is also provided with two extensions 154, one on each side of fulcrum 118 operable to engage a reset pin 156 carried by cradle 85 in an appropriate opening 157 located between pin 133 and spring opening 127 in cradle 85.

Referring now more specifically to Figures 2 and 7 and comparing the cross-sectional drawing of Figure 7 with that of Figure 1, it is there seen that the two phases use practically the same parts except in their operating mechanisms both automatic and manual.

To be more specific, the second phase fault current responsive means (Figure 7) consists of a thermally responsive member 246 soldered to an angle conducting member 240, which carries at its other end one terminal 237 of the second phase of the two-pole circuit breaker. A screw 245 engaging the assembly 240—246 and bearing against the inner U-shaped pocket 292 of molding 10 is used to adjust the tripping times of each pole of the circuit breaker as previously described.

The free end of thermally responsive member 246 is connected to pigtail or flexible conductor 250. Thermally responsive member 246 further carries rigidly secured to it an approximately U-shaped metallic member 275. Metallic member 275 when current flows through thermally responsive member 246 constitutes the magnet for the magnetic fault current responsive means.

A leaf spring 265 is riveted to thermally responsive member 246 near the end at which thermally responsive member 246 is secured to angle 240. Leaf spring 265 extends beyond the free end of thermally responsive member 246 and to the other side of thermally responsive member 246. On its free end leaf spring 265 carries an insulating button 255. Leaf spring 265 also carries the armature 272 for magnet 275. Armature 272 is secured to leaf spring 265 by any appropriate means, for example, a rivet.

As it is evident from this description, no latch is provided for this second section phase, that is, only the first phase or the phase which has the manual operating means is provided with a latch 80 for latching cradle 85.

When a fault occurs in the second phase, either thermally responsive member 246 or magnet 275 will operate and will engage and move tripper bar 70 in such a direction as to unlatch cradle 85 from latch 80 of the first phase, but since cradle 185 of the second phase moves together with cradle 85 of the first phase as previously described, cradle 185 will rotate together with cradle 85 around its pivot pin 336.

This movement around pivot point 336 will carry spring 325 of the second phase to the left (as shown in Figure 7) of movable contact arm 310, thus opening the electrical contact between movable contact 312 and stationary contact 221.

The second phase is also provided with a contact kicking assembly 335 which operates in the same manner as the contact kicking assembly 135 of the first phase.

Each phase is further provided with an arc extinguishing chamber 300 having a plurality of conducting arc extinguishing plates 301. One of the two chambers 300 is located between the stationary contact 21 and movable contact 112, while the other chamber 300 of the second phase is located between the corresponding contacts 221 and 312 of the second phase. As above-men-

tioned, all the other parts of this second phase are the same as those used in the first phase.

When the two circuits protected by this two-phase circuit breaker are to be closed, handle 140 is rotated from right to left of Figure 1. When handle 140 is rotated in this direction, the two contact arms 110 and 310 rotate around fulcri 118 and 150, respectively, to engage their stationary contacts 21 for the first phase and 221 for the second phase. The closing movement is actually a snap action movement in that the two contact arms 110 and 310 will move to close the two phases only after springs 125 and 325, respectively, have gone over center with respect to contact arms 110 and 310, thus biasing the two contact arms 110 and 310 against their respective stationary contacts 21 for the first phase and 221 for the second phase. Since the two contact arms 110 and 310 are biased toward the stationary contacts 21 in one phase and 221 in the other phase, the two contacts 110 and 310 will snap closed at a relatively high speed, thus preventing an arc from being formed or better from being prolonged between movable contacts 112 and 312 on one side and stationary contacts 21 and 221. When a fault current of a certain magnitude develops in one of the circuits, protected by this two phase circuit breaker, and for example, when a fault current develops in the first phase of a circuit breaker, depending on the magnitude of this fault current, either the thermally responsive member 46 or the magnet 75 will operate and will move leaf member 65 against the bias of coil spring 60 to release latch 80 from engagement with extension 86 of cradle 85. Cradle 85 is now free to rotate around its pivot pin 136 bringing with it during its rotation spring 125 until spring 125 is at the right of contact member 110. When spring 125 is at the right of contact member 110, contact member 110 is biased away from stationary contact 21 and will therefore break the electrical contact between movable contact 112 and stationary contact 21. At the same time that spring 125 moved by cradle 85 goes over center, pin 130 also moved by cradle 85 slides from one dimension in slot 131 to the other dimension of slot 131 of contact kicking member 135, thus rotating contact kicking member 135 around its pivot 136 to kick the contact arm 110 and prevent the sticking of contact 112 to 21.

The action of spring 125 provides an excellent quick-break action and, therefore, the arc between contacts 112 and 21 will last for a very small interval of time. Since the second phase cradle 185 is connected by means of tie bar 95 to the first phase, the movement of cradle 25 to open contacts 112 and 21 is accompanied by a similar movement of cradle 185 of the second phase to open the corresponding second phase contacts 312 and 221, and the opening operation of the second phase contacts 312 and 221 and the opening operation of the second phase will be exactly the same as the one described above in connection with the first phase.

If, on the other hand, a fault current is developed in the second phase of the circuits protected by this circuit breaker, the second phase bi-metal member 246 or the second phase magnet 275 will move tripper bar 70 in such a direction as to produce the unlatching between latch 80 and extension 86 of cradle 85, that is, a fault current in the second circuit will operate a fault current responsive means in the second phase 75 which by means of a common tripper bar 70 will

free cradle 485 of the first phase from engagement with latch 480. As above described, when cradle 485 moves to open contacts 412 and 411, a similar action is produced for the second phase since the two cradles 485 and 585 of the first and second phase, respectively, are tied together by tie bar 495. By this means dangerous single phasing is avoided, that is, at no time when a fault occurs will only one of the two circuits remain closed. A fault in any of these two circuits will produce immediate opening of both circuits. As for its manual opening operation, a movement of handle 540 from the left to the right, Figure 1, will produce movements of spring 425, spring 325, contact arm 410 and contact arm 310 similar but in opposite direction to those described in connection with the closing procedure of this circuit breaker. It must be underlined that when the circuit breaker is manually opened, a quick break action is also obtained in that at no time will spring 425 rotate around a fulcrum produced by cradle 485 and boss 65 of housing 48, but a clearance will always be present between spring 425 on one side and cradle 485 and boss 61 on the other. A similar situation exists for the respective elements of the second phase of the circuit breaker.

Referring now to Figures 4, 5 and 6 showing the three-pole embodiment of my present invention, all parts for each of the three phases are the same as those described for the two-pole circuit breaker except for the elements common to all three poles.

In fact, handle molding 520 consists of a handle 540 and in a direction perpendicular to said handle 540 two extensions 541 similarly shaped, one on each side of handle 540. At the ends of these extensions 541 are two cylindrical extensions 543 which by engaging appropriate openings 544 of cover plates 411 and 412 make possible the rotational movement of molding 520 around cylindrical extensions 543. Members 541 actually constitute a single piece having three pairs of grooves 513 in which arms 515 of movable contact arms 510 can rotate.

The central phase in the three-pole circuit breaker corresponds to the first phase of the two-pole circuit breaker above described in that it is the only phase provided with a latch 480 for its cradle 485. This center phase instead of having a leaf spring 265 has, similarly to the first phase of the two-pole circuit breaker, a metallic leaf member 465 (corresponding to member 65 of Figure 1) which at its end 466 carries the tripper bar 470.

Tripper bar 470 can be operated by the center phase now under consideration by means of the thermally responsive means 446 or, should the fault current be very high, by means of magnet 475 secured to thermally responsive member 446 and armature 472 secured to leaf member 465. Leaf member 465 is biased by means of coil spring 461 on pin 455.

Here tripper bar 470 extends through opening 462 in phase separating walls 460 of molding 410 into the two lateral phases. Tripper bar 470 extends sufficiently so that any one of the two leaf springs 565 operated by thermally responsive members (not shown) similar to members 246, or magnets (not shown) similar to magnets 275 of Figure 7, will engage tripper bar 470 and unlatch the central phase latch 480 from engagement with the central cradle 485.

Central cradle 485 now free from engagement with latch 480 will rotate around its pivot 488.

Rotation of central cradle 485 around pivot 488 will produce similar rotations in the other two cradles 585 since all cradles are connected for simultaneous movement by tie bar 495.

Tie bar 495 extending through openings 513 of phase separating walls 460 into the other two phases, actually consists of two center insulating sleeves 496 and two lateral insulating sleeves 497 and 498. Central sleeves 496, cylindrical in shape, have two recesses 499 and 500 one on each end of insulating cylinders 496. Lateral sleeves 497 and 498 instead have axial or longitudinal openings 501 and 502, respectively.

Cradles 485 and 585 all have an opening 503 near the ends 486 and 586, respectively. Each opening 503 is engaged by a reduced diameter portion 504 of a cylindrical pin 505. A metallic hollow cylinder 506 is slid on the extension 504 and riveted there. Thus, cradles 485 and 585 are clamped to pins 505 and will move with pins 505.

Sleeves 497 and 498 are placed around hollow cylinders 506 of the first phase (left phase in Figure 5), and pin 505 of the third phase (right phase in Figure 5). Each sleeve 496, on the other hand, is placed on the hollow cylinder 506 of one cradle, as for example, cradle 485, and on the pin 505 of the adjoining cradle, as for example, cradle 585 of the right phase. It may also be said that pin 505 and hollow cylinder 506 are one riveted assembly which provides projection for mounting sleeves 496, 497 and 498.

Sleeves 497 and 498 serve also to position and retain the current carrying braid 450.

The use of sleeves 496, 497 and 498 completely insulates one phase from the others and makes the mechanism strong enough to resist damage produced by repeated opening or closing operations. Sleeves 497 and 498 and pins 505 are kept in place by the two cover plates 411 and 412, one on each side of the three-pole circuit breaker.

As above mentioned, rotation of central cradle 485 produces, through the bar 495, similar rotations in the other two cradles 585.

Rotation of cradles 485 and 585 brings the springs 525 and 725, respectively, overcenter with respect to the movable contact arms 510 and 710, respectively, thus opening contacts 421 and 512 of the center phase, and also the contacts (not shown) of the other two phases.

At the same time, the three contact kicking members 535 pivoted around pin 536 and provided with an extension 539 are moved by cradles 485 and 585 through a pin 530 carried by cradles 485 and 585 and slots 531 in contact kicking member 535 to kick contact arms 510 and 710 after springs 525 and 725 have gone over center, thus prying the contacts open should they stick to each other.

For reclosing after an automatic opening, the center phase cradle 485 is provided with an opening 587 having a reset pin 586 so that extensions 584 of molding 520 can engage this reset pin 586 and move the cradle 485 back to the original position by rotation of the handle 540 to the full open position (shown in Figure 4). Since the cradles 485 and 585 are tied together through tie bar 495 also, the other two cradles 585 will return to their original position. If now the circuit breaker is manually closed by rotation of handle 540 from right to left (Figure 4), the circuit breaker is again ready to automatically open at fault currents.

When the circuit breaker is to be manually opened, handle 540 is moved from left to right

(Figure 4). Movement of handle 540 produces rotation in cylindrical member 541 around its axis, with the consequent displacement of contact arms 510 and 710 with respect to springs 525 and 725, respectively, until springs 525 and 725 are over center. When springs 525 and 725 are over center, a force directed to the contact open position is produced on the contact arms 510 and 710, thus snapping the contacts 510 and 710 to the open position.

Here the cradles 485 and 585 are so shaped in the region directly facing springs 525 and 725, respectively, that a clearance exists at all times between springs 525 and 725 and that portion of cradles 485 and 585 that faces springs 525 and 725, respectively. It is clear that at no time during the initial manual opening operation will springs 525 and 725 hit the portion of cradles 485 and 585 directly facing springs 525 and 725, to produce harmful prying of contacts before springs 525 and 725 become operative to move the movable contact arms 510 and 710 to the open position.

The closing operation is similar to the above described manual opening operation with all movements occurring in the opposite direction.

In the foregoing I have described my invention solely in connection with specific illustrative embodiments thereof. Since many variations and modifications of my invention will now be obvious to those skilled in the art, I prefer to be bound not by the specific disclosures herein contained but only by the appended claims.

I claim:

1. In a multi-pole circuit breaker, a plurality of fixed contacts, a plurality of movable contact arms carrying movable contacts, said arms having a circuit closed position in which their movable contacts engage said fixed contacts and a circuit open position in which said contacts are disengaged, a plurality of U-shaped cradles pivotally mounted at one end, a tie bar, said tie bar comprising pins and insulating sleeves, said pins engaging said cradles, said insulating sleeves rigidly securing said pins to each other and connecting said cradles for simultaneous motion, a plurality of springs, one end of said springs being secured to said movable arms and the opposite end of said springs being secured to said cradles at the apex of the U-shaped cradles, a pivotally mounted operating handle having a manually operable end on one side of the pivot mounting and having a plurality of notches on the opposite end of the pivot mounting, said movable contact arms being pivotally mounted in said notches and extending substantially in the longitudinal direction of said handle, with said movable contacts on the end opposite the pivotal mounting of said arms, the notches in said handle being on one side of said springs when said handle is in closed position so that said springs apply a closing force on said arms for operating said arms to circuit closed position, and the notches on said handle being on the opposite side of said springs when said handle is in open position so that said springs apply an opening force on said arms for operating said arms to circuit open position, and a plurality of fault current responsive means.

2. In a multi-pole circuit breaker, a plurality of fixed contacts, a plurality of movable contact arms carrying movable contacts, said arms having a circuit closed position in which their movable contacts engage said fixed contacts and a circuit open position in which said contacts are disengaged, a plurality of U-shaped cradles, one of said cradles having one end latched and piv-

otally mounted at its opposite end, the remaining cradles being only pivotally mounted at one end, a tie bar, said tie bar comprising pins and insulating sleeves, said pins engaging said cradles, 5 said insulating sleeves rigidly securing said pins to each other and connecting said cradles for simultaneous motion, a plurality of springs, one end of said springs being secured to said movable arms and the opposite end of said springs being secured to said cradles at the apex of the U-shaped cradles, a pivotally mounted operating handle having a manually operable end on one side of the pivot mounting and having a plurality of notches on the opposite end of the pivot mounting, said movable contact arms being pivotally mounted in said notches and extending substantially in the longitudinal direction of said handle, with said movable contacts on the end opposite the pivotal mounting of said arms, the notches in said handle being on one side of said springs when said handle is in closed position so that said springs apply a closing force on said arms for operating said arms to circuit closed position, and the notches on said handle being on the opposite side of said springs when said handle is in open position so that said springs apply an opening force on said arms for operating said arms to circuit open position, a plurality of fault current responsive means, one of said means having a latch for latching the said cradle, a tripper bar, said tripper bar being secured to said latch carrying fault current responsive means but being operable by the other fault current responsive means, and an insulating housing.

3. In a multi-pole circuit breaker, a plurality of fixed contacts, a plurality of movable contact arms carrying movable contacts, said arms having a circuit closed position in which their movable contacts engage said fixed contacts and a circuit open position in which said contacts are disengaged, a plurality of U-shaped cradles, one of said cradles having one end latched and pivotally mounted at its opposite end, the remaining cradles being only pivotally mounted at one end, a tie bar, said tie bar comprising pins and insulating sleeves, said pins engaging said cradles, said insulating sleeves rigidly securing said pins to each other and connecting said cradles for simultaneous motion, a plurality of springs, one end of said springs being secured to said movable arms and the opposite end of said springs being secured to said cradles at the apex of the U-shaped cradles, a pivotally mounted operating handle having a manually operable end on one side of the pivot mounting and having a plurality of notches on the opposite end of the pivot mounting, said movable contact arms being pivotally mounted in said notches and extending substantially in the longitudinal direction of said handle, with said movable contacts on the end opposite the pivotal mounting of said arms, the notches in said handle being on one side of said springs when said handle is in closed position so that said springs apply a closing force on said arms for operating said arms to circuit closed position, and the notches on said handle being on the opposite side of said springs when said handle is in open position so that said springs apply an opening force on said arms for operating said arms to circuit open position, a plurality of fault current responsive means, one of said means having a latch for latching the said cradle, a tripper bar, said tripper bar being secured to said latch carrying fault current responsive means but being operable by the other fault current responsive means.

4. In a multi-pole circuit breaker, a plurality of fixed contacts, a plurality of movable contact arms carrying movable contacts, said contact arms having a circuit closed position in which their movable contacts engage said fixed contacts and a circuit open position in which said contacts are disengaged, a plurality of U-shaped cradles, a tie bar, said tie bar comprising pins and insulating sleeves, said pins engaging said cradles, said insulating sleeves rigidly securing said pins to each other and connecting said cradles for simultaneous motion, a plurality of springs, one end of said springs being secured to said movable arms and the opposite ends of said springs being secured to said cradles at the apex of the U-shaped cradles, manually operable means, said manually operable means pivotally mounted and having manually operable end on one side of the pivot mounting and having a plurality of notches on the opposite end of said pivot mounting, said movable contact arm being pivotally mounted in said notches and extending substantially in the longitudinal direction of said manually operable means with said movable contacts on the end opposite said pivotal mounting of said contact arms, the notches in said manually operable means being on one side of said springs when said manually operable means is in said closed position so that said springs apply a closing force on said contact arms for operating said contact arms to circuit closed position, said notches on said manually operable means being on the opposite side of said springs when said manually operable means is in open position so that said springs apply an opening force on said contact arms for operating said contact arms to circuit open position, a plurality of fault current responsive means, one of said means hav-

ing a latch for latching one of said cradles, a tripper bar, said tripper bar being secured to said latch carrying fault current responsive means, said tripper bar being secured to said fault current responsive means which do not have a latch, said fault current responsive means which do not have a latch effective to cause disengagement between said one cradle and said latch carrying fault current responsive means through said tripper bar.

5. In a multi-pole circuit breaker, a plurality of fixed contacts, a plurality of movable contact arms carrying movable contacts, said arms having a circuit closed position in which their movable contacts engage said fixed contacts and a circuit open position in which said contacts are disengaged, cradle means for at least one pole of said multi-pole circuit breaker, a fault current responsive means for each pole of said circuit breaker, a fault current responsive means associated with said cradle means for one pole of said circuit breaker having a latch for latching said cradle means, a tripper bar, said tripper bar being secured to said latch carrying fault current responsive means, said fault current responsive means which do not contain a latch keyed to operate said tripper bar.

FELIX E. MYERS.
